UNITED STATES PATENT OFFICE.

EDWARD B. HESS, OF BROOKLYN, NEW YORK.

WIND-SHIELD FOR VEHICLES.

1,244,853.

Specification of Letters Patent.

Patented Oct. 30, 1917.

Application filed March 9, 1916. Serial No. 83,074.

To all whom it may concern:

Be it known that I, EDWARD B. HESS, a citizen of the United States, residing in Brooklyn, in the county of Kings and State of New York, have invented certain new and useful Improvements in Wind-Shields for Vehicles, of which the following is a specification.

This invention relates to wind-shields especially adapted for use in automobiles. Such wind-shields are commonly made in sections so mounted that they may be raised or lowered into or out of the direct line of vision, or set at an angle relatively thereto 15 to suit varying conditions.

According to my invention, I provide a wind-shield which is made in three parts or sections, the lower one of which may be fixed to stand in a vertical position or may 20 be hinged to swing inward. The upper section is pivotally mounted near its upper end to swing outward to a position above the direct line of vision, while a third or auxiliary lower section is made to stand vertically parallel with the main lower section and close to it, or to swing upward into the direct line of vision below the upper section. It is also capable of swinging inward while raised if desired. The organization is such 30 that when desired the front of the automobile may be completely closed by the upper and lower shield sections, or the upper section may be held in a vertical plane in the direct line of vision while the lower sections are swung inward; or the upper section may be extended to assume a position above the direct line of vision while the lower sections are either in open or closed positions. The organization is also such that 35 the auxiliary lower section may be raised to the direct line of vision when the upper section is extended to serve as a rain-guard, while the main lower section is in open or closed position, and furthermore the auxiliary lower section is so mounted that when elevated it may be held in a vertical plane or it may be moved inward to a position above the lower section and in rear of the vertical plane thereof.

50 In the accompanying drawings illustrating my improvements,

Figure 1 is a front elevation showing the upper section of the shield extended and the two lower sections in their lower closed position.

55 Fig. 2 is a similar view showing the auxil-

iary lower section raised to a position in the direct line of vision.

Fig. 3 shows a vertical section of the shield and a portion of the automobile body, 60 the upper and lower sections being all arranged in vertical planes and the front of the automobile completely closed.

Fig. 4 shows a vertical section of the shield with the upper section closed or in 35 a vertical plane, while the two lower sections are swung inward for ventilating purposes.

Fig. 5 is a view similar to Fig. 4 but showing the upper section of the shield ex- 70 tended forwardly.

Fig. 6 is a similar view with the upper section extended forwardly and the two lower sections close together and in closed position.

Fig. 7 is a similar view showing the auxiliary section raised beneath the extended upper section while the main lower section is disposed in a vertical plane and closing the lower portion of the wind-shield opening. 75

Fig. 8 is a view similar to Fig. 7 but illustrates how the lower section may be swung inward.

Fig. 9 is a detail view showing the pivotal connection between the main lower section 85 and the auxiliary lower section.

Fig. 10 is a detail view illustrating the same features of construction.

A part of the hood or casing of an automobile is indicated at A and the wind-shield is located in rear thereof. Posts or standards B rise from the automobile body or casing and between these posts are mounted the three wind-shield sections C, D, and E. Each of these shield sections is preferably formed, as usual, of a suitable marginal frame supporting a transparent plate. The upper section C is pivotally connected near its upper end with the upper ends of the posts B by pivot bolts c which also serve 90 as hand-operated locks to hold the upper section in either its lowered or extended position. Said devices c are of well known construction, being commonly used in connection with wind-shields of the class to which 95 my invention relates.

The shield section C is so mounted that it may hang in a vertical plane in the direct line of vision (Fig. 4), and at this time it may be held firmly in place not only by the 110 devices c but also by the locking devices c' carried by the posts B and each comprising

a knob provided with a threaded shank c^2 adapted to engage a threaded socket c^3 in the side of the adjacent post.

The main lower section D is pivotally connected to the posts B by the devices d which also serve to lock or hold the lower section in any adjusted position.

The auxiliary lower section E is preferably of approximately the same size as the main lower section and it is adapted to lie close to it in a vertical plane, as shown in Figs. 3 and 6, to swing therewith to an inclined position, as shown in Figs. 4 and 5, or to move independently thereof to a raised position as shown in Figs. 7 and 8.

Preferably the section E is connected to the section D by means of brackets e attached to the upper ends of the section D projecting forwardly therefrom and constructed as shown to properly support the auxiliary lower section in such manner that it may, when lowered, lie close to the lower section. The pivotal connection between the main lower section and the auxiliary lower section is indicated at d' and is shown in Figs. 9 and 10 it being a frictional connection of well known construction.

The main lower shield section carries at its lower end a pivoted latch g pressed by a spring g' and serving to hold the auxiliary section in place when the latter is lowered. This latch, however, yields to allow the auxiliary section to swing independently of the lower section whenever such movement is required. The auxiliary section carries on opposite sides near its lower end forwardly projecting arms H formed with holes h and notches h' . When the auxiliary section is raised to the position shown in Fig. 7 with the main lower section in closed position, the holes h of the arms H will be in line with the shanks c^2 of the knobs c' and are engaged thereby to hold the auxiliary section in place. If, however, the main lower section be swung inward, as indicated in Fig. 8, then the shanks of the knobs are made to engage the notches h' as indicated in Fig. 8.

It will be observed that the auxiliary lower section is pivotally connected with the main lower section and may swing inward therewith and that it may be raised and held in the direct line of vision when the lower section is in either its open or closed position. It will furthermore be observed that the auxiliary section swings outward on its hinge connection with the lower section. This it can do with perfect freedom, whereas if it swung inward it would, when applied to many types of automobiles, be interfered with by the steering post. The arrangement contemplates an auxiliary section in an advanced position and in front of the upper and lower wind shields when all three sections are in normal

position, the auxiliary section being located to the rear of and above the engine hood and in front of the wind shield proper, and when so arranged it may be freely elevated to its field of vision position without interference with established parts of the standard automobile. By reference to Fig. 7 it will be seen that the pivotal connection between the two lower sections is such that when the auxiliary section is raised its lower edge is disposed below the upper edge of the main lower section. In this way a joint is formed which effectively prevents the entrance of rain between these sections of the shield.

It will furthermore be observed by reference to Fig. 7 that when desired the auxiliary section may be swung inward as indicated by dotted lines and so held that its front face may be wiped or cleaned if necessary.

My improved wind-shield is of simple construction but its parts may be so adjusted or set as to provide protection or ventilation whenever required.

I claim as my invention:

1. A wind shield comprising: supporting means, an upper shield section pivotally supported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, and an independent pivot connecting the lower and auxiliary sections to move the auxiliary section into an inverted upright position above the lower section when the upper section is in its rain shed position.

2. A wind shield comprising: supporting means, an upper shield section pivotally supported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, and an independent pivot connecting the lower and auxiliary sections to move the auxiliary section into an inverted upright position or into a rearwardly inclined inverted position above the lower section when the upper section is in its rain shed position.

3. A wind shield comprising: supporting means, an upper shield section pivotally sup-

ported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, and an independent pivot connecting the lower and auxiliary sections to move the auxiliary section into an inverted upright position above and overlapping the lower section when the upper section is in its rain shed position.

4. A wind shield comprising: supporting means, an upper shield section pivotally supported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, an independent pivot connecting the lower and auxiliary sections to move the auxiliary section into an inverted upright position above the lower section when the upper section is in its rain shed position, and a latch connecting the lower ends of the lower and auxiliary sections to permit them to swing in unison.

5. A wind shield comprising: supporting means, an upper shield section pivotally supported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, an independent pivot connecting the lower and auxiliary sections to move the auxiliary section into an inverted upright position or into a rearwardly inclined inverted position

above the lower section when the upper section is in its rain shed position, and an alternate locking means for locking the auxiliary section in its upright position when the lower section is in either its upright position or in its rearwardly inclined ventilating position.

5. A wind shield comprising: supporting means, an upper shield section pivotally supported at its upper end on the supporting means to move it from a normal upright position to an outwardly inclined rain shed position, a lower shield section pivotally supported at its upper end on the supporting means to move it from a normal upright position to an inwardly inclined ventilating position, an auxiliary shield section normally parallel to the lower section and mounted to swing with the latter without sliding displacement between the two sections, an independent pivot connecting the lower and auxiliary sections to move the auxiliary section into an inverted upright position above the lower section when the upper section is in its rain shed position, and a latch connecting the lower ends of the lower and auxiliary sections to permit them to swing in unison.

In testimony whereof, I have hereunto subscribed my name.

EDWARD B. HESS.
